CIGARETTE PACKAGE

William Gordon, Brooklyn, N. Y.

Application January 14, 1941, Serial No. 374,331

4 Claims. (Cl. 206—48).

This invention relates to new and useful improvements in a cigarette package.

More specifically, the invention contemplates a cigarette package having one or more of its jackets formed with a pair of spaced parallel slots through which the cover of a book of matches may be passed for mounting the book of matches on the package.

Still further it is proposed that the jacket or jackets of the cigarette package be preformed with the parallel slots so that the book of matches may be conveniently mounted thereon.

A further object of the invention proposes that a simple and effective means be provided for holding the book of matches in position on the cigarette package.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a cigarette package constructed in accordance with this invention.

Fig. 2 is a perspective view similar to Fig. 1, but with a book of matches in position upon the cigarette package.

Fig. 3 is a fragmentary enlarged elevational view of Fig. 1.

Fig. 4 is a fragmentary enlarged vertical sectional view taken on the line 4—4 of Fig. 3.

Fig. 5 is an enlarged fragmentary perspective view of a portion of Fig. 2.

Fig. 6 is a perspective view of the book of matches shown in Fig. 2.

On the drawing, the reference numeral 10 indicates generally a cigarette package of standard construction. This package is provided with an outer jacket 11 of Cellophane, or other sheet material, which is provided with a pair of spaced parallel slots 16 of a length slightly longer than the width of a standard book of matches 18.

The book of matches 18 is of conventional construction. It comprises the cover 17 in which the usual paper matches 21 are mounted. A staple 22 is engaged through the bottom portion of the book of matches to connect the cover with

the sheets of matches. Striking material 24 is mounted on the bottom flap of the book of matches.

The parallel slots 16 have their top and bottom edges reinforced with upwardly and downwardly bent flaps 19 which are slightly narrower than the lengths of the slots 16. Elastic bands 25 are supported by the upwardly and downwardly bent edge portion 19 in a manner so that side portions 25a of the elastic bands extend vertically across the end portions of the slots 16. The elastic bands 25 have top and bottom portions 25b which are disposed within the bends of the edge portions 19 and which are pasted down in position when these edge portions are pasted upon the material of the jacket adjacent the slots 16.

The book of matches 18 is formed with edge niches 26 at locations to be engaged by the side portions 25a of the elastic bands 25 when the book of matches is mounted on the cigarette package as previously explained. Fig. 8 shows the manner in which the elastic bands 25 engage the niches 26.

25 The book of matches 18 may be engaged on the cigarette package shown in Fig. 2 by opening the cover thereof and slipping the cover up through the bottom elastic band 25, then behind the material of the jacket and up and out of the top elastic band 25. The book of matches is then located at a position in which the side portions 25a of the elastic bands engage the niches 26. This serves to firmly support the book of matches in position. When a match is torn out 30 of the book of matches, the book of matches may move slightly due to the resilient supporting action of the elastic bands 25 which prevents the jacket from being torn during this removal operation.

40 While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

50 1. A cigarette package having a jacket formed with a pair of spaced parallel slots through which the cover of a book of matches may be passed for mounting the book of matches on said package, said parallel slots having upwardly and downwardly bent edge portions to reinforce its

top and bottom edges, and elastic bands mounted on said edge portions and having end portions extending across the end portions of said slots for resiliently gripping the edges of said cover.

2. A cigarette package having a jacket formed with a pair of spaced parallel slots through which the cover of a book of matches may be passed for mounting the book of matches on said package, said parallel slots having upwardly and downwardly bent edge portions to reinforce its top and bottom edges, and elastic bands mounted on said edge portions and having end portions extending across the end portions of said slots for resiliently gripping the edges of said cover, and the edge portions of said cover being formed with notches to facilitate said gripping action.

3. A cigarette package having a jacket formed with a pair of spaced parallel slots very slightly longer than the width of a cover of a book of matches, edge portions of a length slightly less than the width of the cover of a book of matches continuing from the material of said jacket defining the top and bottom edges of each of said

slots and bent upwards and downwards for reinforcing said edges, and a continuous expandable member engaged about each pair of edge portions, whereby when the cover of a book of matches is passed through said slots said continuous members will be expanded to grip and hold the edges of said cover.

4. A cigarette package having a jacket formed with a pair of spaced parallel slots very slightly longer than the width of a cover of a book of matches, edge portions of a length slightly less than the width of the cover of a book of matches continuing from the material of said jacket defining the top and bottom edges of each of said slots and bent upwards and downwards for reinforcing said edges, and a continuous expandable member engaged about each pair of edge portions, whereby when the cover of a book of matches is passed through said slots said continuous members will be expanded to grip and hold the edges of said cover, said expandable members, comprising continuous bands of elastic rubber.

WILLIAM GORDON.
